Primary Examiner — Karen S Acker*Assistant Examiner* — Steven B Reinholdt, Jr.(74) *Attorney, Agent, or Firm* — Christensen, Fonder, Dardi & Herbert PLLC(57) **CLAIM**

I claim the ornamental design for a suppressor, as shown and described.

DESCRIPTION

FIG. 1 is a perspective view of a first embodiment of a suppressor showing my new design;
FIG. 2 is a top plan view thereof;
FIG. 3 is a left side view thereof;
FIG. 4 is a rear elevation view thereof;
FIG. 5 is a front elevation view thereof;
FIG. 6 is a perspective view of a second embodiment of the suppressor;

FIG. 7 is a top plan view thereof;

FIG. 8 is a left side view thereof;

FIG. 9 is a rear elevation view thereof; and,

FIG. 10 is a front elevation view thereof.

The broken lines in the center of FIGS. 5 and 10 depict portions of the suppressor that are not claimed. All other broken lines depict the boundaries of the claim and form no part thereof.
